Patented Sept. 5, 1922.

UNITED STATES PATENT OFFICE.

ARTHUR CECIL BUTLER, OF BOSTON, MASSACHUSETTS.

DRAWING MECHANISM.

Application filed February 18, 1921. Serial No. 445,921.

To all whom it may concern:

Be it known that I, ARTHUR CECIL BUTLER, a subject of the King of Great Britain, residing at Boston, in the county of Suffolk 5 and State of Massachusetts, have invented new and useful Improvements in Drawing Mechanism, of which the following is a specification.

This invention relates to apparatus for 10 the drawing of wool, cotton or other fibrous material. While my object is to provide mechanism for drawing out long fibers of wool such as used in the manufacture of worsted yarns, nevertheless it may be effectively used in the drawing of roving composed of relatively short fibers such as 15 is the manufacture of moreno yarns wherein a mixture of wool and cotton are used, or in the drawing of rovings formed of relatively 20 short cotton staple.

The object of the invention is to provide 25 for a greater draft or attenuation of the roving at one operation than can at present be obtained without the production of uneven roving; that is, yarn which varies intermittently in its bulk or diameter. In fact, the invention (as will be explained) is 30 applicable for drawing yarns or rovings both in the English or Bradford, and the French systems. Ordinarily, in the Bradford system of drawing, as well as in the Bradford spinning frame, three, four or more lines or sets of drawing rollers are used, this being the case in worsted mules 35 used in the French system, although in the latter sometimes five lines or pairs of rolls are employed. In any event, the front and back lines of top rolls are comparatively heavily weighted and the longest fibers of 40 the roving are in suspension between the front and back pairs or lines of rolls which are purposely set to suit the roving being drawn. The two or more intermediate lines or pairs of top and bottom rolls serve to support 45 the roving while it is being drawn out between the front and back lines or pairs of rolls. The top intermediate rolls are light, and usually self-weighted, and the fibers, when seized by the front pair of rolls, are 50 drawn from beneath them.

According to my invention, I may substitute for all or some of the intermediate top rolls a gravity cap which rests upon the rolls therebeneath, and permits the fibers to 55 be drawn out evenly and the roving or yarn

to become attenuated without the formation of thin or weak spots. This cap rests loosely on at least two rolls, although it may be so arranged as to engage the roving over only one of the rolls on which it rests. The 60 cap is relatively light, being of sufficient weight, however, to cause the roving or the sliver, as the case may be, to be frictionally engaged by the rolls upon which it rests. What may be termed the rear end of the cap 65 is so curved or hooked as to be maintained in position by the roll on which the said rear end rests, and its front end is curved more or less to approximate the curvature of the roll upon which it in turn rests. Each 70 cap may be of sufficient width for the engagement of a single roving or sliver, or it may be wide enough to engage several, all as may be desired. Preferably the cap is provided intermediate of its ends with a 75 guide for the roving passing beneath it, and this guide may be so formed as to act as a condenser for concentrating the roving or sliver being attenuated or drawn. Since the rear end of the cap is so formed as to take 80 over and rest upon the bottom roll, it is preferably provided with a slot or opening through which the roving or sliver passes to engagement with the bottom roll upon which the rear end of the cap rests. The 85 cap, being supported by rotating rolls, may be easily moved laterally by the lateral movement of the sliver or roving under the impulse of the usual traverse bar in the rear of the lines or pairs of rolls, the cap being 90 sufficiently light to permit its lateral movement without danger of breaking the sliver or roving.

On the accompanying drawings,—

Figure 1 represents, in end elevation, a 95 roll stand embodying the invention.

Figure 2 represents a plan view of the same, the top end rolls being omitted.

Figure 3 represents, in end elevation, another roll stand embodying the invention in 100 which there are six bottom rolls.

Figure 4 represents, in end elevation, still another embodiment of the invention in which a cap is arranged to rest upon three bottom rolls.

Figure 5 represents, in isometric perspective, a cap in its operative position in engagement with the two rolls which are indicated in dotted lines.

Figure 6 represents one of the caps turned 110

upside-down to show the condensing guides which are located intermediate its ends.

Figure 7 illustrates another form of cap in which the forward end is provided with 5 a spring member.

Referring first to Figures 1 and 2, the roll stand 10 is provided with the front top and bottom rolls 11 and 12, and the rear rolls 13 and 14. I have illustrated two intermediate bottom rolls 15, 16, with which 10 may be employed a cap such as I have described. At 17 there is indicated a traverse bar through which the sliver or roving α is passed previous to its being gripped between the rear rolls 13, 14. The intermediate roll 15 is shown as being somewhat larger in 15 diameter than the intermediate roll 16, this not being essential although at times desirable, as will be well understood by those skilled in the art. That is to say, where a 20 relatively long staple is employed in the formation of the sliver or roving, I employ a relatively large roll 15; whereas, when the sliver is formed of relatively short staple, such as cotton or cotton waste, I may use 25 a relatively small roll as at 15. The cap is indicated at 18. It consists of a plate, preferably of metal or other material of relatively high gravity; and, at what I may term its rear end, it is curved as at 19 so 30 as to hook more or less loosely around the roll 16. Its front end 20 is curved to conform to the periphery of the roll 15 upon which it rests by gravity, and towards and from which it may move by a pivotal action 35 about the axis of the roll 16. Preferably the lines of rolls on the roll stand are set at an angle to the horizontal as shown, so that the cap 18 will hang forwardly and 40 downwardly. At its rear curved end 19, the cap is provided with a converging slot 21, through which the roving or sliver α may pass from the rolls 13 and 14 into engagement with the roll 16, and likewise at 45 its front end the cap may be provided with a converging slot 22 through which the roving or sliver may emerge from the roll 15 on its way to the front drawing rolls 11 and 12. Between its ends and on its under 50 side the cap is preferably provided with a guide for the roving, which preferably takes such form as will serve to condense and frictionally engage the roving or sliver passing through it. This guide comprises two 55 forwardly-converging lugs 23, 23, the confronting faces of which may be arcuate or convexly curved as illustrated in Figure 6. As the traverse bar 17 is reciprocated longitudinally of the axes of the rolls for the 60 purpose of causing lateral traverse of the roving or sliver, the engagement of the roving with the front, rear and intermediate guides 21, 22, 23 of the cap cause the cap to move laterally with it.

It will be observed that, by the construc-

tion which I have thus described, the roving or sliver is positively gripped only by the front and rear pairs of rolls between which the actual drawing or attenuation of the roving or sliver takes place. In this 70 case, the roving is supported between these rolls by the intermediate rolls 15 and 16, with which it is lightly maintained in contact by the cap, thereby ensuring the even and uniform attenuation of the roving. 75

In Figure 8, I have illustrated another embodiment of the invention in which, between the front and rear rolls 11, 12, 13, 14, I have provided four lower rolls 24, 25, 26 and 27. For the two rolls 26 and 27, I employ a cap 28 substantially similar to that at 18. I have illustrated a top roll 29 as being associated with the intermediate roll 25, and a cap 30 engaged with the roll 25 and having its front end associated with the larger intermediate roll 24. In this case, the recess or slot at the rear end of the cap 30 is wide enough to receive therein the roll 29 and to permit the necessary traverse motion of the cap in reference to the roll 29. 90

In Figure 4, between the front and rear rolls 11, 12, 13 and 14, I have provided three intermediate rolls 31, 32 and 33, with all three of which there is engaged a single cap 34. In this case the rear curved end of the 95 cap engages the roll 31 and the front curved end engages the roll 33. The intermediate portion of the cap is tangential to the roll 32, or, if desired, it may be slightly concave so as to conform to the convex curvature of the roll 32 without departing from the spirit of the invention. By making this intermediate portion of the cap concave, I increase the frictional engagement of the roving with the roll 32. The cap 34 may be 100 provided with two guides 35, 36, on its under side, similar to those formed by the lugs 23, 23.

If desired, the front end of the cap may be provided with a spring member 37, as 110 illustrated in Figure 7. This spring member may be formed of a leaf spring of thin metal which will yield under light pressure. The forward curved end of the main body of the cap, which overhangs this spring, 115 limits the extent to which it may move and also serves to protect it against injury.

I have not illustrated the mechanism by which all of the various bottom rolls are rotated at the proper speeds, nor the mechanism for reciprocating the traverse bar, as such mechanism is well known, and, per se, forms no part of the present invention.

One of the functions performed by what for convenience I have termed the "roving 125 guide", formed by the lugs 23, is that of frictionally engaging the roving and retarding the loose fibers which are not yet gripped by the front pair of rolls, so that they are not too freely pulled along by those 130

fibers which are gripped by said rolls. Instead of the particular form of guide which I have shown, any other form which will serve the purpose may be employed.

5. What I claim is:—

1. A drawing mechanism comprising bottom rolls, and a gravity cap hung upon one of said rolls and resting loosely upon the other roll and under which the roving 10 passes.

2. A drawing mechanism comprising front and rear pairs of top and bottom rolls, a plurality of intermediate bottom rolls, and a gravity cap resting loosely upon said 15 intermediate rolls and under which the roving passes.

3. A drawing mechanism comprising bottom rolls, and a gravity cap hung upon one of said rolls and resting loosely upon the 20 other roll and under which the roving passes, said cap having a roving guide on its under face intermediate said rolls.

4. A drawing mechanism comprising spaced bottom rolls, and a gravity cap resting on and supported entirely by said rolls to press the roving thereagainst, said cap having one end curved to embrace one of 25 said rolls and having its free end resting loosely on the other roll.

30 5. A drawing mechanism comprising spaced bottom rolls, and a gravity cap resting on and supported entirely by said rolls to press the roving thereagainst, said cap having one end curved to embrace one of 35 said rolls and having its free end resting loosely on the other roll, said cap having a roving guide on its under face intermediate its ends.

6. A drawing mechanism comprising front and rear top and bottom drawing 40 rolls, and intermediate bottom rolls, in combination with a gravity cap loosely embracing one of the intermediate bottom rolls and resting loosely upon one or more of the intermediate bottom rolls. 45

7. A drawing mechanism comprising spaced bottom rolls, and a gravity cap resting on and supported entirely by said rolls to press the roving thereagainst, said cap having one end curved to embrace one of 50 said rolls and having its free end resting loosely on the other roll, said cap having a guide in said curved end to receive the roving.

8. A drawing mechanism comprising 55 spaced bottom rolls, and a gravity cap resting on and supported entirely by said rolls to press the roving thereagainst, said cap having one end curved to embrace one of said rolls and having its free end resting 60 loosely on the other roll, said cap having guides at each end for the roving.

9. A drawing mechanism comprising a traverse bar, spaced bottom rolls, and a cap resting upon and supported entirely by said 65 rolls, and at one end embracing one of said rolls, said cap having a roving guide for causing the roving to pass between said cap and said rolls, the parts being so related that the lateral movement of the roving by 70 the traverse bar causes the said cap to move laterally therewith.

In testimony whereof I have affixed my signature.

ARTHUR CECIL BUTLER.
